[57] CLAIM

I claim the ornamental design for a stuffed animal, as shown and described.

DESCRIPTION

FIG. 1 is a perspective view of a stuffed animal showing my new design;

FIG. 2 is a front elevational view of the front side of the stuffed animal shown in FIG. 1;

FIG. 3 is a back elevational view thereof;

FIG. 4 is a right side elevational view of the right end of the stuffed animal shown in FIG. 1;

FIG. 5 is a left side elevational view of the left end of the stuffed animal shown in FIG. 1;

FIG. 6 is a top plan view of the stuffed animal shown in FIG. 1; and,

FIG. 7 is a bottom plan view of the stuffed animal shown in FIG. 1.
